UNITED STATES PATENT OFFICE.

TAKEBE HASE, OF SAN FRANCISCO, CALIFORNIA.

RUBBER COLLAR.

1,414,640.

Specification of Letters Patent. Patented May 2, 1922.

Application filed August 18, 1920. Serial No. 404,312.

To all whom it may concern:

Be it known that I, TAKEBE HASE, a citizen of Japan, residing in the city and county of San Francisco and State of California, have invented a new and useful Improvement in a Rubber Collar, of which the following is a specification.

My invention relates to soft rubber collars of the fold-down type wherein the thickness 10 of material is reduced along the line of fold.

The prime object of my invention is to provide an improved collar of soft elastic material of waterproof character.

Another object is to provide an improved 15 soft collar of the type described, arranged to reduce the thickness of material along a fold.

Another object is to provide a collar of the type described having overlapping fastening tabs beveled to reduce the thickness of the 20 collar at the throat.

I accomplish these and other objects by means of the device disclosed in the drawings forming a part of the present specification wherein like characters of reference are used 25 to designate similar parts throughout said specification and drawings and wherein:

Fig. 1 is a view of the inner side of my improved turn-down collar in unfolded position.

Fig. 2 is a sectional view of my improved 30 collar in turned down or folded position.

Fig. 3 is a sectional view similar to Fig. 2, the section being taken along a plane disclosing the interfolded fastening tab.

Fig. 4 is a broken plan view of the front 35 portion of my improved collar.

Referring to the drawings my invention is seen to reside in the specific construction therein disclosed, the numeral 1 being used 40 to designate in general a collar formed from an outer ply 2 of soft flexible rubber or the like and an inner ply 3 of similar material cemented or otherwise permanently secured thereto, said inner ply 3 being in two portions to form a turn-down portion 4 and a neck band 6. The inner ply portions meet 45 along the line of fold 7 and the meeting edges 8 are beveled to reduce the thickness of material along the fold 7.

Fastening tabs 9 are formed upon the ends 50 of the neck band 6 and arranged to overlap when the collar is fastened around the neck of a wearer, said tabs 9 being provided with beveled edges 11 along the top thereof. The 55 edges 11 are beveled upon opposite sides of the neck band 6 thereby causing the beveled

portions to be inwardly and outwardly faced to present a beveled surface and an edge of reduced thickness to the throat of the wearer. The beveled edge 11 of the interfolded 60 tab 9 fits neatly between the neck band 6 and the turn-down portion 4 as shown in Fig. 3 of the drawings, thereby preventing excessive thickness of material at the fold and permitting the portion 4 to be folded 65 thereover without causing a bulge.

The beveled edges 8 are provided to prevent undue thickness of the collar at the fold thereby giving a neater appearance to the 70 collar and affording greater comfort to the wearer. When folded, the beveled edges lie adjacent as disclosed in Fig. 2 of the drawings, the outer ply 2 folding neatly thereover without stress on the material and without causing excessive outward flare such as 75 would occur when the inner ply portions meet with blunt edges along the line of fold 7.

Small apertures 12 are punched at the desired points for engagement by the ordinary collar button 14, the elasticity of the rubber permitting the apertures 12 to be readily stretched over the button 14 and the collar retained firmly fastened thereon, thereby overcoming the difficulties attendant 85 in fastening hard rubber or starched collars and preventing the loosening of the fastening common to ordinary soft collars.

The rubber sheeting constituting the inner and outer plies 2 and 3 may be made of any 90 desired color by dyeing or otherwise coloring the rubber before molding. The sheeting is of a soft and pliable character to afford comfort to the wearer, and must be made of a sufficient weight or thickness of 95 material to cause the collar to stand in the desired position when secured about the neck band of a shirt.

Having thus described my invention what I claim as new and desire to secure by Letters Patent is:

1. A fold down rubber collar comprising an outer ply; an inner ply secured thereto and formed in portions constituting a neck band and a turn down portion, said portions arranged to meet along the line of fold; and beveled edges formed upon the inner ply portion adjacent the line of fold to reduce the thickness of the collar when folded thereon.

2. A fold down collar comprising an outer 110 ply of flexible rubber; an inner ply of similar material secured thereto and formed in

portions constituting a neck band and a turn down portion, said portions arranged to meet along the line of fold; and beveled edges formed upon the inner ply portions adjacent to the line of fold to reduce the thickness of the collar when folded thereon; fastening tabs arranged to overlap when the collar is secured around the neck of a wearer, said tabs having beveled edges to reduce the thickness of the collar at the throat.

3. A fold down collar comprising an outer ply of flexible rubber; an inner ply of similar material secured thereto and formed in portions constituting a neck band and a turn down portion, said portions arranged to meet along the line of fold; and beveled edges formed upon the inner ply portions adjacent the line of fold to reduce the thickness of the collar when folded thereon; fastening tabs arranged to overlap when the collar is secured around the neck of a wearer, said

tabs being beveled upon opposite sides adjacent the top thereof to reduce the thickness of the collar at the throat.

4. A fold down collar comprising an outer 25 ply of flexible dyed rubber; an inner ply of similar material cemented thereto and formed in portions arranged to meet along the line of fold; beveled edges formed upon the inner ply portions adjacent the line of 30 fold to reduce the thickness of the collar when folded thereon; fastening tabs formed upon the ends of the collar and arranged to overlap when the collar is secured around the neck of a wearer, said tabs being beveled 35 upon opposite sides adjacent the top thereof to reduce the thickness of the collar at the throat.

In witness whereof I hereunto set my signature.

TAKEBE HASE.
